ATTORNEYS.

UNITED STATES PATENT OFFICE.

KERRIGAN MARK MANOOKIN, OF LOS ANGELES, CALIFORNIA, ASSIGNOR TO WAGNER-WOODRUFF COMPANY, A CORPORATION OF CALIFORNIA.

DESIGN FOR A LIGHTING UNIT.

Application filed July 23, 1923. Serial No. 6,833. Term of patent 3½ years.

To all whom it may concern:

Be it known that I, KERRIGAN MARK MANOOKIN, a citizen of the United States, residing at Los Angeles, in the county of Los Angeles and State of California, have invented a new, original, and ornamental Design for Lighting Unit, of which the following is a specification, reference being had to the accompanying drawing, forming part thereof.

In the drawing:

Fig. 1 is an elevation of the lighting unit. Fig. 2 is a horizontal section thereof taken on line 2—2 of Fig. 1.

I claim:

The ornamental design for a lighting unit, as shown.

KERRIGAN MARK MANOOKIN.

Witnesses:

MARIAM C. COEN,
AGNES F. DAUGHERTY.
